DROP SEAT GARMENT

Erick O. Fellroth, Minneapolis, Minn., assignor
to Martin Brothers Company, Minneapolis,
Minn., a corporation of Minnesota

Application June 14, 1939, Serial No. 279,046

7 Claims. (Cl. 2—79)

My invention relates to garments formed with a drop seat and having belt straps attached to the garment and connected to the drop seat for drawing the drop seat into closing position and holding the same in such position.

An object of the invention resides in providing a garment of such character which will be extremely serviceable.

Another object of the invention resides in providing a garment in which the drop seat is securely held in closing position.

A still further object of the invention resides in providing a garment in which the drop seat is prevented from sagging when in closing position.

An object of the invention resides in providing a garment in which the body of the garment may be held gathered by means of the belt straps.

A still further object of the invention resides in attaching each belt strap at one end to the garment and at the other end to the drop seat and in slidably mounting buckle members upon the belt straps adapted to be moved forwardly to draw the drop seat into closing position.

An object of the invention resides in attaching loops to the sides of the garment and in passing the belt straps through the loops.

A still further object of the invention resides in causing the portion of the drop seat adjacent the connection of the belt straps thereto or a metal member attached to the drop seat at such locality to engage the loops and hold the garment gathered.

Another object of the invention resides in providing hooks attached to the drop seat for engagement with the loops in the garment to support the drop seat from the loops and prevent sagging of the drop seat.

A still further object of the invention resides in forming shoulders on the hooks for engaging the loops to hold the garment gathered.

Other objects of the invention reside in the novel combination and arrangement of parts and in the details of construction hereinafter illustrated and/or described.

In the drawing:

Fig. 1 is a front elevational view of a garment illustrating an embodiment of my invention.

Fig. 2 is a rear elevational view of the structure shown in Fig. 1 and illustrating the parts in one position.

Fig. 3 is a view of a portion of the structure shown in Fig. 2 and similar thereto and illustrating the parts in another position.

Fig. 4 is a view similar to Fig. 3 showing the drop seat in lowered position.

Fig. 5 is a fragmentary plan sectional view taken on line 5—5 of Fig. 2 and showing the buckle members unattached.

In the use of garments formed with drop seats where the drop seat is adapted to be closed by means of belt straps connected therewith, sagging of the garment usually occurs. Also, where garments of a size larger than that required for the user is employed, the garment has an unsightly appearance when the drop seat is closed. The present invention provides a construction whereby the body of the garment may be held gathered at the sides thereof to leave the rear and front portions smooth when an over-sized garment is applied to the user and the belt straps sufficiently tightened to cause the garment to fit the user. At the same time a construction is provided in which the drop seat becomes supported independently of the straps to prevent sagging of the drop seat.

The invention may be embodied in several different types of garments, such as garments having a jacket and trousers combined, or a bib or suspenders combined with trousers, or with trousers alone. For the purpose of illustrating the invention I have shown a garment, indicated in its entirety by the reference character A. This garment is of the type having a jacket 10 and trousers 11 connected therewith.

The trousers 11 comprise legs 12 and 13, which are seamed together along the sides of the garment, as indicated at 14. The trousers are formed with two front portions 15 and 16 and a rear portion 17. The front portions 15 and 16 may be secured together through a placket 18 and concealed buttons. Such, being well known in the art has not been shown in detail in the drawing.

The jacket 10 consists of two front portions 21 and 22 and a back 23 connected to the same with seams 24 which lie in continuation of the seams 14. The front portions 21 and 22 are secured together by means of buttons 25 and lie in continuation of the front portions 15 and 16 of the trousers 11. The jacket 10 includes a collar 26 and sleeves 27 and 28.

The waistline of the garment is designated at 29 in the drawing. It will be noted that the lowermost portion 31 of the back 23 extends below the waistline 29, as best shown in Fig. 4. Formed as a continuation of the rear portion 17 of the trousers 11 is a drop seat 32, the upper marginal portion 33 of which is disposed sub-

stantially at the waistline 29 of the garment. To the marginal portion 33 of the drop seat 32 is attached a hem 34 which extends completely across the same and which strengthens and supports the drop seat. The material from which the hem 34 is constructed extends outwardly beyond the drop seat and is seamed at its edges to form a pair of belt straps 35 and 36 connected to the drop seat and projecting outwardly therefrom. These belt straps thus become attached at one end to the drop seat 32. The other ends 37 of the belt straps are secured to the garment substantially at the seams 14 and 24 thereof.

Slidable upon the belt straps 35 and 36 are two loops 38 which have secured to them adjusting straps 39. The adjusting straps 39 have attached to them complementary buckle members 41 and 42 which are adapted to be hooked together to connect the belt straps to one another, as shown in Fig. 1. The construction of the buckle members 41 and 42 and the adjusting straps 39 being well known in the art, the same will not be described in detail in this application although it can readily be comprehended that any suitable construction may be used for the purpose.

The invention proper utilizes two loops 43 and 44 for each belt strap 35 and 36. Since these loops operate in the same identical manner with both belt straps, only the loops used with the belt strap 35 and their mode of operation will be described. The loop 43 is attached to the garment substantially at the locality of the seams 14 and 24 and the loop 44 is attached to the garment rearwardly thereof. Both of these loops are situated at the elevation of the waistline 29. The strap 35 is threaded through the two loops 43 and 44, as shown in Figs. 5 and 4, and the parts are so arranged that the loops 43 and 44 are disposed between the loop 38 and the locality of issuance of the strap 35 from the drop seat 32.

Attached to the strap 35 and to the drop seat 32 is a plate 45 which is constructed with eyes 46 through which stitches may be taken to attach the same to the garment. This plate is constructed with a hook 47 and with a shoulder 48 directly opposite the hook.

The use of the garment is as follows: When the buckle members 41 and 42 are disengaged and released, the belt straps slide along the loops 43 and 44 and the drop seat may be lowered, as shown in Fig. 4. When the buckle members are drawn forwardly, the drop seat is raised and drawn into closing position. The adjusting straps 39, when adjusted for a large size person, permit the hooks 47 to engage the rearward loops 44. These hooks may be manually hooked into the loops 44 before the belt straps are secured together. Position of the parts, when the hooks are so engaged, is shown in Fig. 2. When in such position the shoulders 48 on the plates 45 engage the loops 44 and prevent rearward movement of the lateral portions of the back 23 of the jacket, thus maintaining the jacket properly applied. If the belt straps are shortened sufficiently, the hooks 47 may be engaged with both the loops 43 and 44, as shown in Fig. 3, in which case gathers are formed in the garment confined principally to the material between the said loops 43 and 44. It will thus become evident that the garment can be made to fit small or large persons and regardless of the size of the person can be made to fit smoothly and snugly on the back of the wearer. It will readily be comprehended that the loop 44 engages both the marginal por-

tion of the drop seat 32 and the shoulder 48. If desired, the plate 45 may be dispensed with and the supporting of the drop seat procured solely through the belt straps and the movement of the loops resisted solely through engagement with the marginal portions of the drop seat.

The advantages of my invention are manifest. The garment can be made to properly fit persons of different sizes. By means of the loops employed the belt straps are positively supported with reference to the garment and held in predetermined position. The gathering of the garment can be confined principally to the material between the loops. By the use of the plate having the shoulder and hook, the drop seat is hooked into closing position and will not readily become detached. At the same time the loops are in position through engagement with the shoulders of the plates. The invention can be constructed at a nominal cost and is easy to operate.

Changes in the specific form of my invention, as herein disclosed, may be made within the scope of what is claimed without departing from the spirit of my invention.

Having described my invention, what I claim as new and desire to protect by Letters Patent is:

1. A garment including trousers having a rear opening therein, a drop seat connected to the trousers and covering said opening, said drop seat being free at the upper end and terminating substantially at the waistline of the garment, a pair of belt straps each attached at one end to the garment and connected to the drop seat at the waistline thereof, complementary buckle members connected to the belt straps and adapted upon forward movement to draw the drop seat into closing position, loops attached to the garment on opposite sides of the garment, said belt straps passing through said loops, hooks movable with the drop seat and adapted to engage said loops, said hooks holding the drop seat suspended from the loops, and shoulders on said hooks for engagement with the loops to prevent rearward movement of the portions of the garment connected to the loops engaged by the shoulders.

2. A garment including trousers having a rear opening therein, a drop seat connected to the trousers and covering said opening, said drop seat being free at the upper end and terminating substantially at the waistline of the garment, a pair of belt straps each attached at one end to the garment and connected to the drop seat at the waistline thereof, complementary buckle members connected to the belt straps and adapted upon forward movement to draw the drop seat into closing position, loops attached to the garment on opposite sides of the garment, said belt straps passing through said loops, and hooks attached jointly to the belt straps and drop seat for engaging the loops to support the drop seat from the loops.

3. A garment including trousers having a rear opening therein, a drop seat connected to the trousers and covering said opening, said drop seat being free at the upper end and terminating substantially at the waistline of the garment, a pair of belt straps connected to the drop seat at the waistline thereof and adapted to extend about the forward portion of the garment, means for securing the forward portions of the belt straps together, loops attached to the garment on opposite sides of the garment, said belt straps passing through said loops, hooks movable with the

drop seat and adapted to engage said loops, said hooks holding the drop seat suspended from the loops, and shoulders on said hooks for engagement with the loops to prevent rearward movement of the portions of the garment connected to the loops engaged by the shoulders.

4. A garment including trousers having a rear opening therein, a drop seat connected to the trousers and covering said opening, said drop seat being free at the upper end and terminating substantially at the waistline of the garment, a pair of belt straps connected to the drop seat at the waistline thereof and adapted to extend about the forward portion of the garment, means for securing the forward portions of the belt straps together, loops attached to the garment on opposite sides of the garment, said belt straps passing through said loops, and hooks attached jointly to the belt straps and drop seat for engaging the loops to support the drop seat from the loops.

5. A garment including trousers having a rear opening therein, a drop seat connected to the trousers and covering said opening, said drop seat being free at the upper end and terminating substantially at the waistline of the garment, a pair of belt straps connected to the drop seat at the waistline thereof and adapted to extend about the forward portion of the garment, means for securing the forward portions of the belt straps together, pairs of loops attached to the garment on each side thereof, each pair including a loop disposed at the side of the garment and another loop disposed rearwardly thereof, each belt strap passing through the loops of one pair, and an engaging member for each belt strap disposed in proximity to the locality of issuance of the same from the drop seat, said engaging member being adapted to engage either of the loops of the pair of loops through which the belt strap passes.

6. A garment including trousers having a rear

opening therein, a drop seat connected to the trousers and covering said opening, said drop seat being free at the upper end and terminating substantially at the waistline of the garment, a pair of belt straps connected to the drop seat at the waistline thereof and adapted to extend about the forward portion of the garment, means for securing the forward portions of the belt straps together, pairs of loops attached to the garment on each side thereof, each pair including a loop disposed at the side of the garment and another loop disposed rearwardly thereof, each belt strap passing through the loops of one pair, and a hook for each belt strap movable with the drop seat and disposed in proximity to the locality of issuance of the belt strap therefrom, said hook being adapted to engage either of the loops of the pair of loops through which the belt strap extends.

7. A garment including trousers having a rear opening therein, a drop seat connected to the trousers and covering said opening, said drop seat being free at the upper end and terminating substantially at the waistline of the garment, a pair of belt straps connected to the drop seat at the waistline thereof and adapted to extend about the forward portion of the garment, means for securing the forward portions of the belt straps together, loops attached to the garment on opposite sides of the garment, said belt straps passing through said loops, hooks movable with the drop seat and adapted to engage said loops, said hooks having edges disposed along the edges of the belt straps and having shoulders projecting outwardly beyond the edges of the belt straps, said first named edges preventing roping of the belt straps and said shoulders restraining movement of the drop seat along the waistline in either direction relative to said loops.

ERICK O. FELLROTH.
